CLAIM

The ornamental design for a card studio display, as shown and described.

DESCRIPTION

FIG. 1 is a perspective view of the card studio display showing our new design;

FIG. 2 is a rear perspective view thereof;

FIG. 3 is a front elevation view thereof;

FIG. 4 is a rear side elevation view thereof;

FIG. 5 is a top plan view thereof;

FIG. 6 a bottom plan view thereof; and,

FIG. 7 is a right side elevation, which is identical to the left side elevation view thereof.

The broken lines shown in the drawings are for the purpose of illustrating environmental structure and form no part of the claimed design.
